UNITED STATES PATENT OFFICE.

MORTIMER L. BRADLEY, OF JOHNSON CITY, TENNESSEE.

CAP FOR TRUSS-PADS.

1,314,123.

Specification of Letters Patent. Patented Aug. 26, 1919.

Application filed March 15, 1919. Serial No. 282,888.

To all whom it may concern:

Be it known that I, MORTIMER L. BRADLEY, citizen of the United States, residing at Johnson City, in the county of Washington and State of Tennessee, have invented certain new and useful Improvements in Caps for Truss-Pads, of which the following is a specification.

This invention relates to an improved cap for abdominal truss pads and has as its primary object to provide a cap designed for use upon the ordinary oval shaped truss pad.

As is well known, abdominal trusses as now on the market are generally equipped with oval shaped pads. I have found from practical experience that a pad of this nature tends to press into the rupture and separate the edges thereof so that the rupture is prevented from healing. On the other hand, I have also found from practical experience that by presenting a flat surface to the rupture, the pad is not only prevented from separating the edges of the rupture but, on the other hand, a reverse result is obtained, namely, a tendency is created to draw the edges of the rupture together so that they may properly heal. The present invention, therefore, has as a further object to provide a cap which may be employed in connection with substantially any conventional type of oval shaped pad and which when applied, will provide a flat surface adapted to overlie the rupture.

And the invention has as a still further object to provide a cap which will be simple in construction and which may be readily attached to an ordinary truss pad and as easily detached therefrom.

Other and incidental objects will appear hereinafter. In the drawings:

Figure 1 is a fragmentary perspective view showing my improved cap in position upon the pad of a conventional type of abdominal truss.

Fig. 2 is a fragmentary sectional view more particularly illustrating the manner in which the cap is engaged with the truss pad, and

Fig. 3 is a perspective view showing the cap in detail, this view being on an enlarged scale.

Referring now more particularly to the drawings, I have shown my improved cap in connection with a conventional type of

truss employing the usual padded spring body band 10 at one end of which is mounted an ordinary oval shaped pad 11. In carrying the invention into effect, I employ, in constructing my improved cap, a base plate 60 or bottom wall 12 provided with a marginal flange 13 and having an opening 14 formed centrally therethrough. The base plate is substantially rectangular and the opening 14 is of similar contour. Normally coacting 65 with the base plate is a cap body 15. This cap body is also rectangular in shape and is adapted to fit snugly within the flange 13 of the base plate 12 frictionally coacting therewith to be properly held upon the 70 base plate. The cap body is provided with a flat top wall 16. Preferably, the cap body as well as the base plate 12 are each formed of suitable resilient sheet material.

In applying the device, the base plate 12 75 is first fitted over the pad 11, as shown in Fig. 2 of the drawings, the pad being received through the opening 14 in the plate and the plate being moved inwardly upon the pad until the pad binds within said opening. Thus, this base plate will be firmly connected with the pad. The cap body 15 is then engaged with the base plate to overlie the pad, it being observed in this connection that the top wall 16 of the cap body 80 will rest against the pad to be prevented thereby from sagging. Consequently, the flat top wall 16 of the cap will, when the truss is applied in use, be presented to the rupture and will overlie the rupture so that 85 the flat surface of said wall will tend to draw the edges of the rupture together in order that it may heal. I consequently provide a particularly meritorious device. At the same time, the cap is of unusually 90 simple construction and may, without difficulty, be readily applied to a pad of substantially any conventional type of abdominal truss.

Since the cap body is detachable from the 100 base plate of the device, the cap body may be removed at any time desired so that a firm grip may be had upon the base plate for adjusting this plate upon the truss pad. Furthermore, this construction provides an 105 arrangement whereby the cap body may be detached and this body partly filled with a suitable filler or packing so that when the body is again replaced, all looseness between the cap body, base plate and the truss 110

pad will be eliminated. Also, it will be seen that in the instance of an unusually large pad, too large for the opening in the base plate, the base plate may be removed from 5 the cap body and the cap body fitted directly over the pad.

Having thus described the invention, what is claimed as new is:

1. A device of the character described including a closed hollow cap comprising a base plate and cap body freely separable from the plate, the base plate being provided with an opening adapted to receive a truss pad projecting into the cap body.
- 10 2. A device of the character described including a closed hollow cap comprising a base plate, and a cap body frictionally engaged with the base plate, the plate being

provided with an opening adapted to receive a truss pad projecting into the body. 20

3. As a new article of manufacture, a cap for truss pads including a base plate provided with an opening whereby the plate may be impinged upon a truss pad and thus frictionally connected therewith, and a hollow 25 cap body mating with the base plate.

4. A device of the character described including a hollow cap provided with an opening adapted to receive a truss pad projecting into the cap, the cap being adapted to 30 receive a filling for taking up the space between the walls of the cap and the portion of the pad projecting therein whereby to firmly support the cap over the pad.

In testimony whereof I affix my signature. 35
MORTIMER L. BRADLEY. [L.S.]
